(57) **CLAIM**

The ornamental design for a beverage brewer, as shown and described.

DESCRIPTION

FIG. 1 is a perspective view of a beverage brewer according to an embodiment of the invention.

FIG. 2 is a front view of the beverage brewer of FIG. 1;

FIG. 3 is a rear view of the beverage brewer of FIG. 1;

FIG. 4 is a right side view of the beverage brewer of FIG. 1.

FIG. 5 is a left side view of the beverage brewer of FIG. 1.

FIG. 6 is a top view of the beverage brewer of FIG. 1; and,

FIG. 7 is a bottom view of the beverage brewer of FIG. 1. The broken lines in the drawings are included for the purpose of illustration and form no part of the claimed design.
